UNITED STATES PATENT OFFICE.

SIMON C. COLLINS, OF FALMOUTH, PENNSYLVANIA.

RAIL-FASTENER.

1,103,129.

Specification of Letters Patent. Patented July 14, 1914.

Application filed October 7, 1913. Serial No. 793,918.

To all whom it may concern:

Be it known that I, SIMON C. COLLINS, a citizen of the United States, residing at Falmouth, in the county of Lancaster and State of Pennsylvania, have invented a new and useful Rail-Fastener, of which the following is a specification.

The device forming the subject matter of this application is a fastener, adapted to be assembled with a pair of rail ends, to prevent the rail ends from having relative longitudinal movement.

The invention aims to provide novel means whereby the rails will be maintained assembled with the rail retainers, without piercing the rails for the reception of the common and well known securing bolts.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 shows the invention in top plan; Fig. 2 is a fragmental longitudinal section wherein sundry parts appear in elevation; Fig. 3 is a side elevation, parts being sectioned and removed; Figs. 4 and 5 are cross sectional details; Fig. 6 is a side elevation of one rail retainer; Fig. 7 is a side elevation of the other rail retainer; Fig. 8 is a perspective showing one form of base plate; Fig. 9 is a perspective showing a modified form of base plate; Fig. 10 is a perspective showing a modified form of lock stud, adapted to be employed in connection with that form of base plate which is depicted in Fig. 9.

In the accompanying drawings, a pair of rails are shown and denoted by the numeral 1. Each rail, in its flange portion is equipped with a notch 2. Base plates 3 lie beneath the rails 1, and each base plate 3 is equipped with a transverse flange 4. As depicted in Fig. 8, a diamond shaped lug 5 upstands from the base plate 3 and is formed integrally therewith. The base plate 3 may be provided with a longitudinal slot 6. In the flange of each rail there is an opening 7 receiving a headed fastener 8 (see Fig. 4).

A rail retainer 9 is shown, the same being

provided with a reinforced boss 10 located opposite the flange 4 of the base plate 3. In the side face of the rail retainer 9 there is a notch 11. The rail retainer 9 is equipped in its lower edge with an opening 12 which receives the base plate 3, there being a finger 14 at one end of the opening 12 which finger extends beneath the base plate. To the retainer 9, adjacent the other end of the opening 12 a latch 15 is pivoted as indicated at 16.

The invention includes a second rail retainer 17 having an opening 18, a finger 19, and a latch 20 which is pivoted as indicated at 21 as hereinbefore described.

If desired, a pin 22 may be passed through the flange of the rail 1, the lower end of the pin being received by the base plate 3. In the side face of the retainer 17 there is a notch 23 into which the pin 22 fits, the rail retainer 17 overhanging the upper end of the pin.

In practical operation, the latch 15 is manipulated so that the retainer 9 may be straddled upon the base plate 3, the inner end of the latch 15 and the finger 14 engaging beneath the base plate. Thus, the rail retainer 9 may be located between the lug 5 and the flange 4 of the base as will be understood best when Fig. 8 is compared with Fig. 2. The rail retainer 17 is mounted in place in a similar manner. From the foregoing it will be seen that because the diamond shaped lugs 5 on the base plates are interengaged with the notches 11 of the rail retainer 9 and with the notches 2 of the rails 1, relative longitudinal movements between these elements will be prevented, there being no necessity for piercing the rails 1 to form bolt holes.

The headed fastener 8 which is lodged in the opening 7 of the rail 1 engages with the slot 6 in the plate 3, and thus relative longitudinal movement between the rails is prevented. The head of the fastener 8 is wider than the slot 6, and consequently, the fastener cannot drop through the slot. Upward movement of the fastener 8 is prevented by reason of the fact that the rail retainer 17 overhangs the fastener as clearly shown in Fig. 4.

The lower end of the pin 22 passes through the flange of the rail 1 and abuts against the base plate 3. Since the pin 22 is engaged in the notch 23 of the rail retainer 17, each rail is interlocked with the retainer, and

relative longitudinal movement between the rails will not be possible. Further, the pin 22 cannot move upwardly, because the retainer 17 overhangs the upper end of the pin 5 as will be understood best from Fig. 5.

Any or all of the foregoing means will be found thoroughly effective for the ends in view.

It has been stated hereinbefore that the 10 lug 5 is formed integrally with the base plate 3. If desired, the diamond shaped lug may be fashioned separately from the base plate, as indicated at 27 in Fig. 10. Under such circumstances, the base plate is constructed as shown in Fig. 9, the base plate 15 being indicated generally by the reference character 24 and including if desired, the slot 26 and the flange 25. It will be seen that the detachable lug 27 exercises its function, since through its use, the adjacent ends 20 of the rails are interlocked with the rail retainer 9. Both the fixed lug 5 and the detachable lug 7 may be described as being supported by the base plate.

Having thus described the invention, what 25 is claimed is:—

1. In a device of the class described, a base plate; a rail resting thereon and having a notch; a rail retainer interlocked with the 30 plate and having a notch; and a stud sup-

ported by the plate and engaged in the notches to hold the rail against longitudinal creeping.

2. In a device of the class described, a base 35 plate having a slot; a rail resting on the plate; a securing element mounted in the rail and engaged in the slot; and a rail retainer extended across the upper end of the securing element and interlocked with the plate.

3. In a device of the class described, a rail; an upright projection at one side thereof; a rail retainer having a groove in which the projection is received; and a base plate 45 with which the retainer is interlocked.

4. In a device of the class described, a rail; a base plate upon which the rail rests; a pin extended through the rail and abutting against the base plate; and a rail retainer 50 overhanging the pin and provided in its side face with a groove receiving the pin.

In testimony that I claim the foregoing as my own, I have hereto affixed my signature in the presence of two witnesses.

his
SIMON C. X COLLINS.
